UNITED STATES PATENT OFFICE.

ELMER DONNELL, OF WEBSTER GROVES, MISSOURI.

DESIGN FOR A PAPER-WEIGHT OR STATUETTE.

44,953.

Specification for Design.

Patented Dec. 2, 1913.

Application filed September 29, 1913. Serial No. 792,524. Term of patent 14 years.

To all whom it may concern:

Be it known that I, ELMER DONNELL, a citizen of the United States, residing at Webster Groves, in the county of St. Louis and State of Missouri, have invented a new, original, and ornamental Design for Paper-Weights or Statuettes, of which the following is a specification, reference being had to the accompanying drawing, forming a part thereof.

The drawings illustrate a paper weight or statuette, showing my new design.

In said drawings Figure 1 is a front elevation, Fig. 2 a rear elevation, Fig. 3 an ele-

vation viewed from the right, and Fig. 4 an elevation viewed from the left.

I claim:

The ornamental design for a paper weight or statuette, as shown.

In testimony whereof, I have signed this specification in the presence of two subscribing witnesses, this 25th day of September, 1913.

ELMER DONNELL.

Witnesses:

R. M. LAWRENCE,
J. D. RIPPEY.
